UNITED STATES PATENT OFFICE.

DANIEL G. CHILSON, OF JEROME, ARIZONA, ASSIGNOR TO THE UNIVERSITY OF ARIZONA, OF TUCSON, ARIZONA.

PROCESS OF AND DEVICE FOR LOCATING ORE.

Application filed March 25, 1922, Serial No. 546,752. Renewed February 25, 1924.

To all whom it may concern:

Be it known that I, DANIEL G. CHILSON, a citizen of the United States, residing at Jerome, in the county of Yavapai and 5 State of Arizona, have invented certain new and useful Improvements in Processes of and Devices for Locating Ore, of which the following is a specification.

The invention relates to ore locating devices, and has as an object the provision of 10 an apparatus and process which will make it possible to locate unknown ore deposits, and to determine the extent of known ore deposits.

15 Illustrative embodiments of the invention are shown in the accompanying drawings, in which—

Fig. 1 is a diagrammatic showing of a complete apparatus showing the application 20 of the same to a known deposit of ore;

Fig. 2 is one form of electrifying device;

Figs. 3, 4 and 5 are different forms of 25 listening apparatus;

Figs. 6, 7 and 8 show forms of electrifying apparatus.

While it is possible to operate the apparatus by applying the electrifying device to two grounded contacts where the location 30 of the ore is not known, yet it is preferred, as illustrated in Fig. 1, to apply the electrifying device to one contact 10 in connection with a known body of ore, and a second ground 11 at any place adjacent thereto.

The form of electrifying device shown in 35 Fig. 1 comprises a buzzer 12, one terminal of which is connected with a source of energy 13, and the other terminal to a pivoted armature at 14, which is normally against a back contact 15, which in turn is connected 40 by means of wires 16, 17, with a switch 18, normally open. A wire 19 leads from the switch to the source of energy 13. In shunt with the buzzer are the grounded contacts 10 and 11 connected by means of wires 20, 21, 45 respectively. The making and breaking of the buzzer circuit by its automatic action will cause electromagnetic waves to be applied to the earth through grounded contacts 10 and 11; which electromagnetic waves will 50 be radiated from the body of ore 22. If a

proper listening apparatus be connected between two other grounded contacts, as 23, 24, which may be separated a distance of from less than 10 to more than 100 feet, the waves affecting a telephone receiver 25 connected in the listening device will vary in intensity as the contacts are applied to the ground nearer or farther from a subterranean body of ore.

The body of ore to which the contact 10 60 may be applied may have its limits plotted with a close approximation by the use of a listening device, and unknown ore bodies in the vicinity at variable but considerable distances from the known ore body with which contact was made may be located since they appear to act as independent sources of electromagnetic waves, and the intensity of sound in the receiver increases as the separate bodies of ore are approached and is 65 greatest when the contacts 23, 24 are applied to the ground directly thereover. In this manner the extent of the separate ore bodies as well as their location can be determined.

To avoid confusion with extraneous 70 sounds it is desirable to have the electrification of the grounded contacts of the electrifying device intermittent. An apparatus which is convenient for this purpose is shown in Fig. 2 wherein the buzzer 12 is utilized, as in the device shown in Fig. 1, being connected by means of wires 27, 28 to battery 13, and by means of wires 29 to movable contact 30, the back contact 31 being connected by means of wires 32, 33 to contact 34. A central contact 35 is carried preferably by a spring extension upon the pivot of a pendulum 36 having a weight 37 which may be adjustable. The pivot 38 of the pendulum is connected by a wire 39 with the 80 battery 13. Carried by the pendulum rod 36 is a core 40 projecting into a solenoid 41 which solenoid is connected by wire 42 with a contact 43 placed adjacent to the removable contact 35 and by wire 44 to wire 28 and battery 13. In shunt with the buzzer 12 are the ground contacts 10 and 11, as in the device of Fig. 1.

When it is desired to start the device of Fig. 2 into operation the pendulum 37 may 90

be started to swinging by the hand of the operator so as to bring contacts 34 and 35 together. This will energize the buzzer circuit through a circuit from battery 13, wires 5 28 and 27, buzzer 12, wire 29, armature 30, contact 31, wires 32, 33, contacts 34, 35, pivot 38, wire 39 to battery.

The opposite vibration of the pendulum by its own weight will break the circuit described by separation of contacts 34, 35 and 10 will close contacts 35, 43, at the same time withdrawing the core 40 from the solenoid. The closing of the contacts mentioned will 15 complete a circuit from battery 13 through wires 28, 44, solenoid 41, wire 42, contacts 43, 35, pivot 38, wire 39, to battery, thus energizing solenoid 41 and drawing in the core 40. The movement of the core 40 will be 20 sluggish, due to the momentum of the pendulum bob 37, and the period of the pendulum may be adjusted by moving the bob 37. As the core 40 is drawn into the solenoid the 25 solenoid circuit will be broken and the buzzer circuit again made, thus providing a series of pulsations of electromagnetic waves.

A suitable form of listening device is shown in Fig. 5, in which 45 is a vacuum tube of a well known construction having a filament 46, grid 47 and a plate 48. To heat 30 the filament 46 a battery 49 is connected thereto by means of wires 50, 51, 52, an adjustable resistance 53 being placed in the circuit for the purpose of adjusting the temperature of the filament 46, according to 35 well known practice.

The ground contacts 10, 11 are connected between the grid 47 and the filament 46 and a high potential battery is connected between the filament 46 and the plate 48. If 40 desired the telephone receiver 25 may be connected directly in this circuit. The receiving device may be made more delicate however by the provision of an amplifying coil having its primary 55 connected in 45 circuit with the high potential battery 54, the filament and plate and a secondary coil 56 connected at one terminal with the grid 57 of a second vacuum tube 58, and its other terminal with the filament 59 thereof. To 50 light the filament of tube 58 a battery 60 is shown, and if still further amplification of the currents is desired the plate 61 of the vacuum tube 58 may be connected to primary 62 of a second amplification coil, which 55 coil is connected with the high potential battery 63 which in turn is connected with the filament 59. The secondary coil 64 of the second amplifying coil is shown connected to the grid 65 of a third vacuum 60 tube 66, which tube has a telephone receiver 25 connected in circuit with its filament and plate. When the contacts 10 and 11 of this apparatus are applied to the ground even very faint waves will be perceptible through said telephone receiver 25,

through the well known amplifying effect of the series of vacuum tubes and amplifying coils.

Instead of using ground contacts the device of Fig. 3 may be used wherein a vacuum tube 67 is provided with the usual lighting battery 68 in circuit with its filament 69, and is shown as having an open spiral 70 connected to its grid. The spiral 70 has a multiplicity of coils and may be turned 75 about a nonconducting rod for support. The telephone receiver 25 is shown as connected in circuit with a high potential battery 71, the plate 72 and filament 69. It is found that electromagnetic waves in the 80 earth over which this apparatus is carried are most appreciable when the free end of the spiral points directly away from an ore body. A straight piece of wire may be used instead of the spiral 70 but with inferior 85 results. A second form of listening apparatus which does not necessitate grounded contacts is shown in Fig. 4, in which a pick-up coil 73 is connected in circuit with the filament and grid 74 of a vacuum tube 75, which is provided with the usual battery 76 for lighting its filament, and in which the plate circuit is energized by the high potential battery 77 having the 90 telephone receiver 25 in the plate circuit. 95

The signals received by this form of apparatus will be loudest when the pick-up coil 73 is held perpendicular to the ore body and will increase in intensity as the position over the ore body is approached. It 100 will be understood that the primary of an amplifying coil may be connected, instead of the telephone receiver 25, in either of the forms of apparatus shown in Figs. 3 or 4 with the secondary thereof in circuit 105 with the grid of a second vacuum tube after the practice illustrated in Fig. 5.

It is possible to detect the electromagnetic waves by the simple apparatus shown in Fig. 1, comprising merely the grounded 110 contacts 23, 24, connected to a telephone receiver 25. The distance from the ore body will be readily indicated in this form of the device by the distance which it is necessary to separate the contacts 23, 24 in order to detect the sound in the receiver. The strength of the signal will also vary, depending upon whether a line connecting the ground contacts 23, 24 is parallel to the strike of the ore body or perpendicular thereto, or in some intermediate position.

Modified forms of electrifying devices are shown in Figs. 6, 7 and 8. The device of Fig. 6 is conveniently portable and yet delivers more current than a buzzer with greater flexibility for measurements. This device comprises a vacuum tube 78 provided with the filament 79, adjustable resistance 80, and filament lighting battery 81. The primary winding 82 of an audio 130

frequency transformer is shown as connected to the plate 83 of the vacuum tube and to a high potential battery 84 by means of wires 85 and 86 respectively. The battery 84 is shown as connected to the filament 79 by means of wires 87, 88 and also to one terminal of the battery 81 by means of wire 87. An intermediate winding 89 of the transformer is shown as connected 10 to the grid 90 of the vacuum tube by means of wires 91, 92, a variable condenser 93 being connected between the coil 89 and the grid. The filament 79 is connected to wire 92 by means of a wire 94, a suitable 15 resistance 95 being included therein. The second terminal of coil 89 is connected by means of wires 95, 96, to battery 81 at an intermediate point thereof, a condenser 97 being placed between wires 95, 96. A third 20 coil 98 of the transformer has its terminals connected to the ground contacts 10 and 11.

The combination of circuits described, is, as is well known, unbalanced, and will give rise to fluctuations of currents which 25 will produce electromagnetic waves projecting from the grounded contacts 10 and 11 when the capacity of the variable condenser 93 is properly adjusted. If the values of the different portions of the circuit 30 are correct without an adjustment by the condenser 93 this condenser may be omitted.

The forms of electrifying device shown in Figures 7 and 8 comprise alternating 35 current generators, as at 99 and 100. The form of Fig. 7 shows the generator 99 connected to the terminals of one coil 100 of a transformer with a circuit closer in the circuit at 101. To protect the coil 100 a 40 pair of condensers 102 and 103 are connected in the circuit upon each side of the coil 100, the second plates of which condensers are grounded as at 104. The other coil 105 of the transformer is shown as 45 connected to one side of a spark gap 106 and the ground at 11 with a condenser 108 connected in shunt of coil 105. The other side of the spark gap 106 is connected to the ground contact 10. It is possible to 50 use the generator, as shown at 100, in Fig. 8, with simply a circuit closer 107 and the ground contacts 10 and 11. By use of the desired one of the forms of electrifying devices with the desired form of listening device the extent of known ore deposits as 55 well as the dips and the strikes of known bodies of ore may be determined. Also known bodies of ore may be located and their extent as well as their dips and strikes 60 may be determined.

When the form of listening device of Fig. 3 is used the depth of a body of ore below the surface may be roughly determined by holding the spiral at points whose 65 distance apart is known and by noting the

angle at which the spiral must be held to cause the loudest sounds in the receiver.

All the forms of apparatus shown operate better with so-called "sulphide ores" 70 than with other ores.

Minor changes may be made in the physical embodiment of the invention and the steps of the process without departing from the spirit.

I claim as my invention:

1. The process of locating or exploring bodies of ore comprising applying a contact to the earth and a second contact to a known body of ore, connecting an electromagnetic wave producing device between 80 said contacts, placing an electromagnetic wave detecting device at points distant from the point of contact with the known body of ore and determining the presence or absence of bodies of ore adjacent such 85 distant points by the intensity of the electromagnetic waves at those points.

2. The process of locating or exploring bodies of ore which comprise transmitting electromagnetic waves from a known body 90 of ore, placing an electromagnetic wave detecting device at a point distant from the known location of the body of ore aforesaid and determining the outlines or absence of an adjacent body of ore by noting 95 the strength of received electromagnetic waves.

3. The process of locating or exploring bodies of ore which comprises transmitting 100 electromagnetic waves from a known body of ore, intermitting the production of said waves at appreciable intervals, placing an electromagnetic wave detecting device at points adjacent the surface of the earth and distant from the known location of the body of ore aforesaid and determining the outlines or absence of an underlying body of ore by noting the strength of received 105 electromagnetic waves.

4. Apparatus for ore location comprising, 110 in combination, a buzzer, one coil terminal of said buzzer connected to a source of energy and the other coil terminal connected to a movable armature, a contact adapted to be grounded and connected to one of said terminals, the second pole of said source of energy connected to the back contact of said buzzer and to a second contact adapted to be grounded whereby electromagnetic waves may be produced emanating from 115 said contacts while grounded and means to break the circuit through said buzzer comprising a pendulum carrying a movable contact and a solenoid to cause vibration of said pendulum.

5. Apparatus for ore location comprising, 120 in combination, a buzzer, a solenoid, a source of electrical energy, one coil terminal of said buzzer connected to said source of energy, the other coil terminal connect- 125

ed to the movable armature of the buzzer, one of said terminals also connected to the solenoid, a contact adapted to be grounded and connected to one of said terminals, a 5 pendulum, a core for said solenoid connected to said pendulum, a movable contact carried by said pendulum, a pair of stationary contacts adapted to coact alternately

with said movable contact, one of said stationary contacts connected to the back contact of said buzzer, the other to said solenoid, a contact adapted to be grounded connected to said last named stationary contact, said pendulum connected to the source of energy.

DANIEL G. CHILSON.
